HOSIERY DRYING FORM

Thomas W. Prosser and John H. Wahlbeck, Kankakee, Ill., assignors to Paramount Textile Machinery Co., Chicago, Ill., a corporation of Illinois

Application October 3, 1931. Serial No. 566,758

13 Claims. (Cl. 223—17)

Our invention relates to hosiery drying forms, and more particularly to an internally heated form which is adapted to the drying of hosiery composed of fabric portions having differing textures or weights.

The purpose and manifold advantages of the apparatus of the instant disclosure are substantially set forth in our copending application filed May 23, 1931, S. N. 539,488, with this exception: 10 that the form of the present invention contemplates either the use of steam alone, or a combination of steam and hot water, as a heating agent, whereas that of the application referred to may be used with either steam or hot water. 15 The principal object of the present invention is the provision of a form which is adapted to uniformly dry within a minimum time a hosiery article having fabric portions of differing texture. The apparatus is particularly intended for use in 20 a mill wherein steam only is available, and the installation necessary to provide a hot water system of drying is undesirable or its cost prohibitive.

It is well known in the finishing of hosiery that 25 a hot water system possesses many advantages, especially in respect of the availability of "lower-than-boiling" temperatures for the boarding of chiffon goods which cannot be finished to a merchantable appearance within the range of temperatures afforded by steam. Our invention makes available a hot-water method of finishing in a manufactory where the only heating medium obtainable is steam.

Because of the fact that steam is used, and 35 also that the temperature of steam may be readily varied over a wide range by a simple control, a regulation of the results obtainable by use of the present device is facilitated to a point where, if desirable, individual control may be provided 40 for each table of forms, or even for each form if such a fine degree of flexibility is required.

Essentially, the present device attains the results just recited by the maintenance of different temperatures on the surface of a single form, so 45 proportioned to the different fabric portions of a stocking that the lower temperature condition acting to dry the sheerer portions will be effective simultaneously with the higher temperature condition acting to dry the reinforced portions thereof, and thus finishing the whole stocking in the shortest possible time. This result is made possible without the disadvantages attendant upon drying a sheer stocking at the high temperature of rapid production or the lessening of production 50 incident to the drying of the reinforced portions

at a temperature low enough to be harmless to the sheer portions.

The above and further objects of our invention will appear from the following description, reference being had to the accompanying drawings. It is to be understood that many modifications of the principles of our invention may be made without departing from the spirit and scope thereof, and that the following description and the drawings are only typical and not comprehensive.

In the drawings:

Figure 1 is an external view in elevation of one form of this invention with a stocking superposed thereon in drying position;

Fig. 2 is an enlarged longitudinal section of the form of Fig. 1 with parts broken away;

Fig. 3 is a transverse sectional view through a form embodying a modified arrangement of the form of Fig. 2;

Fig. 4 is a longitudinal section, similar to that of Fig. 2, illustrating a further modification of our apparatus;

Figs. 5 and 6 are elevations, partly in section, showing still further modifications.

Referring to Figs. 1 and 2, the numeral 1 designates generally an internally heated, hosiery drying form of a common type, which comprises essentially a closed shell constructed in any conventional manner and arranged for support according to standard practice. In the lower end of the form 1 are provided the integral bosses 2, 3 and 4 into which are respectively inserted the steam inlet nozzle 5, the outlet nozzle 6, and the drain plug 7.

Secured in the lower end of the form and communicating with the nozzle 5 is the lower end of a delivery pipe or tube 8 (Fig. 2) which extends upwards within the form and terminates close to the upper end thereof, so as to provide a delivery opening in the indicated location. A drain tube 9 is also fastened in the lower end of the form but in communication with the nozzle 6, and the upper end of this tube terminates at a line 12 which approximately follows the boundary of the reinforced toe, sole and heel portions 13 of a stocking boarded on the form, as shown by dotted lines in Fig. 2 and more clearly in Fig. 1.

The operation of the device is as follows: Assuming that the form is entirely devoid of heating medium and that it is desired to prepare the form for operation, the attendant opens a valve and allows steam at a predetermined temperature and pressure to enter the nozzle 5 and pass upwardly through the tube 8. At this time, since

the form is cold, the entering steam will condense and water will collect in the form to the top of the tube 9. Thereafter, any water of condensation will overflow this tube and leave the form 5 by way of the nozzle 6. Further passage of steam into the form maintains a steam heated region above the line 12 as well as serving to heat the body of water below the line 12 to a temperature somewhat lower than the temperature of the 10 steam. Such condensate as may be formed from time to time assists in maintaining the temperature of the water. The water is further heated by the passage of steam through the tube 9, it being evident that both overflowing water and 15 outgoing steam pass through that tube.

The ultimate result is a form filled with hot water to include those portions which contact with the sheer areas of the stocking and with steam in the part which is overlaid by the reinforced portions 20 of the stocking. The several parts and the steam factors are preferably so arranged that a proportioned drying effect is obtained in which the hotter, or steam-heated, zone serves to dry the heavier fabric portions in substantially the 25 same length of time as the water-heated zone dries the sheerer fabric portions. Different combinations of fabric structure will necessitate different combinations of drying temperatures and such variations may be readily secured by suitable changes in the sizes of tubing as well as 30 adjustments in the steam pressure and temperature so as to produce the flow of medium which will give the desired result. The form may be emptied by removing the plug 7.

An important modification of the form shown 35 in Figure 2 is depicted in Fig. 3. This view shows a typical cross-section through steam inlet and drain tubes 14 and 15, respectively, which are concentrically arranged with the tube 14 occupying the innermost position. These tubes function 40 similarly to the tubes 8 and 9 of Fig. 2, but by placing the tube 14 within the tube 15, the condensate and low temperature steam passing through the annular space between the two tubes 45 exerts an insulating effect on the steam passing through the tube 15 and thus lowers the rate of heat transmission to the body of water in the form. In this manner, the temperature of the water which effects the drying of the sheerer portions 50 of the stocking is maintained lower than the corresponding temperature of the water of the form of Fig. 2, while the temperature of the steam effecting the drying of the reinforced foot and heel portions of the stocking remains substantially 55 the same.

In Fig. 4, there is illustrated a modification of the invention, which although somewhat higher in cost of manufacture, attains a more efficient drying of the welt 16 of the stocking (Fig. 1).

The bosses 17, 18 and 19, the nozzles 20 and 21, the plug 22 and the tube 23 function similarly to the corresponding elements in Fig. 2. However, in this embodiment, there are provided two transversely disposed septa 24 and 25 within the form 60 which are spaced a small distance apart for a purpose to be explained and located approximately at the junction 26 of the welt and sheer leg portions of the stocking (Fig. 1). The lower septum 24 is provided with a boss 27 and the upper 65 septum with an opening 28 through which a tube 29, fastened at its lower end in the boss 27 extends upwardly to a point corresponding to the upper end of the tube 9 of Fig. 2.

The function of that portion of the form above 75 the septum 25 is exactly the same as described for

the form shown in Fig. 2. As in the latter instance, steam passes downwardly through the tube 29 and enters the space 30 below the septum 24 so that two steam spaces are provided in the 80 form. The result is a steam heated zone coextensive with the welt 16 of the stocking and hence a drying action thereof comparable to that obtaining in the reinforced foot 13 (Fig. 1). Since the amount of condensate passing through the tube 29 is relatively small when the form has attained its operating temperatures, it and the condensate formed in the chamber 30 is rapidly drained away through the nozzle 21 to a conventional form of trap (not shown).

Hence, in this modification, there is obtained a refinement of the results accomplished by the form of Fig. 2, namely, proportional drying of the foot, leg and welt portions, whereby these 90 portions of varying fabric texture are dried in substantially the same period of time.

The purpose of the space between the septa 24 and 25 is to insulate the body of water above the septum 25 from the action of the steam below the septum 24, and so maintain each of these 100 regions at their proper drying temperature. The spacing of the septa may be varied as desired. If it is desired to empty the form at the close of operations, the drain plugs 22 and 31 are removed, the latter being mounted in the septa 24 and 25 and preferably in alignment with the plug 22 for 105 convenience of access.

In Fig. 5 is illustrated a further modification of the apparatus under discussion, in which the numeral 32 designates a hollow drying form having a supporting portion 33, a leg portion 34 and 110 a foot portion 35. The portions 33 and 34 are angularly disposed with respect to each other so that the form 32 will occupy an inclined position when mounted on the customary support. Further, the angular relation between the leg portion 34 and the foot portion 35 is more in accord 115 with standard practice in this respect for the purpose of preventing wrinkling of the fabric in the region of the angle, than is the case with the forms hereinbefore described. Extending 120 upwardly within the form are the steam inlet and overflow pipes 36 and 37, respectively, both pipes being given an appropriate bend in order to conform to the inclination of the leg portion 33, with the pipe 36 terminating close to the upper side 125 of the foot portion 35 and the overflow pipe 37 at a line 38 substantially marking the junction of the sheer leg and reinforced foot portions of a stocking which may be superimposed on the form.

The operation of the form in Fig. 5 is precisely 130 the same as that illustrated in Fig. 2, but it will be particularly noted that, by reason of the inclination of the form, it is possible to locate substantially correctly the water level in the form so as to make it accord with the aforesaid junction line in a form which is arranged with proper 135 relations existing between the leg and foot portions.

Referring to Fig. 6 which illustrates a still further modification of a drying form of the upright 140 type, the numeral 39 designates such a form having correct dispositions of the leg and foot portions thereof and which is provided internally with a septum 40 which closely conforms to the junction line between the sheer leg and reinforced foot portions. The septum 40 divides the form 39 internally into a chamber 41 and a chamber 42, upper and lower, respectively. The chamber 41 is intended to serve as a steam heating chamber and is supplied by a steam inlet 145

5 pipe 44 which extends upwardly through the form, as described in connection with the other forms, through the septum 40 and terminates close to the upper side of the chamber 41. A discharge pipe 45 also extends upwardly through the chamber 42 and terminates on the upper side of the septum 40. The lower end of the chamber 42, which is a water heating chamber, is closed by a drain plug 43.

10 In operation, the form 39 is first inverted, or placed in some other convenient position, and the drain plug 43 removed in order to permit the insertion of a suitable amount of water within the chamber 42. The plug is then replaced and 15 the form placed in an upright position as shown and steam introduced through the inlet pipe 44. It will be obvious that the steam entering by the pipe 44 and leaving by the pipe 45 will create a steam heated zone in the chamber 41 and further, that the passage of steam through the indicated pipes will heat the water in the chamber 42 to a temperature somewhat less than that obtaining in the chamber 41, but which is entirely adequate to dry the sheer leg portions of 20 the stocking. The normal expansion of the water in the chamber 42 may be compensated for at the beginning of the operation by introducing a quantity of water into the chamber 42 less than the full volume of the latter, the difference being 25 filled by the expansion of the water. The form 30 may be regarded as a variation of the form 32 in respect of the correct angular relations obtaining between the foot and leg portions thereof, but it is possible in the form illustrated in Fig. 35 6 to take advantage of the possibilities of the present invention in a form of the upright type.

We claim:

1. A hollow, hosiery drying form for receiving a heating medium comprising a steam inlet pipe 40 and an overflow pipe for condensate extending lengthwise within the form, the upper end of the overflow pipe terminating substantially at a line approximating the junction of the sheer leg and reenforced foot portions of a stocking boarded on the form and the upper end of the inlet pipe extending beyond and terminating closer to the upper end of the form than the outlet pipe.

2. A hollow, hosiery drying form for receiving a heating medium comprising a steam inlet pipe 50 and an outlet pipe for condensate extending upwardly from the lower part of the form, said inlet pipe terminating close to the upper end of the form and said outlet pipe at a lower point corresponding substantially to the junction of the sheer and reenforced portions of a stocking boarded on said form.

3. A hollow, hosiery drying form for receiving a heating medium comprising a steam inlet pipe and an outlet pipe for condensate extending upwardly from the lower part of the form, said inlet pipe terminating close to the upper end of the form and said outlet pipe at a lower point corresponding substantially to the junction of the reenforced and sheer portions of a stocking boarded on said form to thereby define steam-heated and water-heated zones substantially coextensive with said stocking portions, respectively, the adjacent surfaces of said zones being in contact.

4. A hollow, hosiery drying form for receiving a heating medium comprising a steam inlet pipe 70 extending interiorly from the lower part of said form close to the top thereof, a transverse septum dividing said form into upper and lower chambers and located substantially in line with the junction of the welt and leg portions of a

stocking boarded on said form, and an overflow pipe for condensate extending from said septum to a point lower than the upper end of the inlet pipe and substantially in line with the junction of the sheer leg and reinforced foot portions of said stocking, the lower end of said overflow pipe communicating with said lower chamber. 80

5. A hollow, hosiery drying form for receiving a heating medium comprising means for supplying steam to said form, means for maintaining the water of condensation formed from said steam at a predetermined level to establish a water-heated zone for the sheer leg portion of a stocking boarded on said form, and means for maintaining steam heated zones substantially coextensive with the welt and reinforced foot portions of said stocking. 85

6. A hollow, hosiery drying form for receiving a heating medium comprising upper and lower chambers, a steam inlet pipe extending interiorly from the lower part of said form close to the top thereof, the division between said chambers being located substantially in line with the junction of the welt and leg portions of a stocking boarded on the form, and an overflow pipe for condensate extending from said division line to a point substantially in line with the junction of the sheer leg and reenforced foot portions of said stocking, the lower end of said overflow pipe communicating with said lower chamber. 90

7. A hollow, hosiery drying form for receiving a heating medium comprising concentrically disposed, steam inlet and condensate overflow pipes extending lengthwise within the form, said inlet pipe being innermost, the upper end of the inlet 100 pipe terminating close to the adjacent end of the form and the upper end of the overflow pipe terminating at a lower point and substantially at a line marking the junction of the sheer leg and reenforced foot portions of a stocking boarded on the form. 105

8. A hollow, hosiery drying form for receiving a heating medium and comprising a supporting portion, leg and foot portions, said leg portion being angularly disposed with respect to said supporting portion, a steam inlet pipe and an overflow pipe for condensate extending lengthwise within the form, the upper end of the inlet pipe terminating close to the upper end of the form and the upper end of the overflow pipe terminating at a lower point and substantially at a line marking the junction of the sheer leg and reenforced foot portion of a stocking boarded on the form, the angular relation between the leg and supporting portions being sufficient in conjunction with the angular relation between the foot and leg portions to maintain the level of the condensate approximately coincident with the said junction line. 110

9. A hollow, upright, hosiery drying form for receiving a heating medium comprising an internal septum located in the foot portion of the form and substantially in the line marking the junction of the sheer leg and reenforced foot portions of a stocking boarded on the form, said septum dividing the interior of the form into an upper and a lower chamber, a steam inlet pipe and an outlet pipe extending lengthwise within the form with their upper ends passing through said septum and terminating within said 120 upper chamber, and water completely filling said lower chamber, said water being heated by the passage of steam through said pipes. 125

10. A hosiery drying structure comprising a hollow form adapted to externally receive in dry- 130
